TWO-CYCLE ENGINE

Roland Chilton, Ridgewood, N. J., assignor to
 Wright Aeronautical Corporation, a corpora-
 tion of New York

Application June 8, 1931, Serial No. 542,898

4 Claims. (Cl. 123—53)

This invention relates to the type of two cycle-engine wherein adjacent cylinders are united in pairs by common combustion chambers, one cylinder of each pair being provided with inlet ports and the other with exhaust ports, the ports being over-run by the pistons to control the admission to and emission from the engine of the fuel charges and burnt gases, respectively.

In engines of the above class it is desirable 10 that both the exhaust opening and closing precede the corresponding events at the inlet ports, for which purpose out-of-phase pistons, with the pistons in the exhaust cylinder leading, are desired. This permits supercharging and prevents 15 loss of charge thru the exhaust ports. Such out-of-phase piston requirement further complicates the problem of obtaining good balance which is already a difficulty from the fact that two pistons may not reach dead center together without 20 also being fired simultaneously whereby the chief advantage of the two cycle-engine would be lost. (In four cycle-engines it is desirable to have one piston on its firing dead center and one piston on its exhaust dead center simultaneously which 25 conforms to the requirements for balance with conventional cylinder dispositions).

Opposed pistons with dual crankshafts geared together, and paired cylinders disposed in two banks over a common crankshaft, are among the 30 expedients that have been used in two cycle constructions, but the former gives a relatively bulky engine and the latter does not give good balance with even firing intervals and has involved bent connecting rods in the effort to keep the top of 35 the cylinders close together to avoid excessive length of the cylinder joining combustion chambers.

There is a form of engine, however, having the cylinders arranged around and parallel to the 40 power shaft. By importing the paired cylinder arrangement into such a cylinder disposition the present invention achieves the desired out-of-phase piston motion in an extremely compact engine which may be accurately balanced and 45 which has evenly spaced firing impulses. The preferred embodiment comprises double ended pistons in aligned cylinders giving an engine with combustion chambers at each end.

When an even number of cylinder pairs is 50 used, then, for equal spacing of the firing impulses on two cycle operation, the cylinders of one end are paired by common combustion chambers in staggered relation to the combustion chambers pairing the cylinders of the other 55 end. On the other hand, even firing impulses

are obtained with the common combustion chambers at one end opposite those at the other end in the case where an odd number of pairs is used, and this is the preferred embodiment because it permits of unsymmetrical circumferential spacing of the cylinders which would give odd lengths to the connecting combustion chambers in the case of the staggered arrangement. 60

The close spacing of the cylinders of each pair as compared to the angle between the cylinders 65 of adjacent pairs permits a desirable reduction in the out-of-phase angle between the pistons of each pair which gives the desired timing for the ports. The increased space between adjacent pairs affords room for the intake and exhaust 70 pipes which may thus be disposed within the general overall diameter of the cylinders whereby the outside dimensions of the engine are reduced, thus contributing to the extreme compactness which is one of the objects of this invention, which is here illustrated as an aircraft 75 power plant wherein minimum diameter is of great importance.

In the drawings, wherein like reference characters denote like or corresponding parts, 80

Fig. 1 is a longitudinal section on the line 1—1 of Fig. 2;

Fig. 2 is an end view in part section on the line 2—2 of Fig. 3, and

Fig. 3 is an inverted plan view in section on the 85 line 3—3 of Fig. 2.

Referring first to Fig. 1, the main engine body is divided into front and rear jacketed combustion chamber sections 10 and 12 secured to intermediate jacketed sections 14 and 16 and provided 90 with cylinder liners 18a and 18b. These liners or sleeves 18a and 18b are provided with ports, the preferred construction of which is fully described in my co-pending application Serial No. 525,494 filed March 26, 1931 and does not form 95 a part of the present invention, the cylinder disposition of which may be practiced with any suitable cylinder construction. Supported on bearings 20 in the main engine body is the power shaft 22 having an angular crankpin 24 on which 100 is mounted the spider 28 on the ball bearings 30. The preferred construction of the angular crank mechanism is described in detail in my co-pending application Serial No. 532,552 filed April 24, 1931 and is not a part of the present invention, 105 which is applicable to any angular crank or wobble plate mechanism.

The arms of the spider 28 engage the double ended pistons 32 by joints 34, the preferred construction for which forms the subject matter of 110

said co-pending application Serial No. 532,552 filed April 24, 1931 and is not a part of the present invention with which other piston driving connections may be used.

- 5 Referring to Fig. 2 and considering that the direction of rotation of the power shaft 22 is clockwise the sleeve 18a will comprise an exhaust cylinder and the sleeve 18b an inlet cylinder and these are united to constitute a pair by the 10 common combustion chambers 36 (Figs. 1 and 3). It will be seen that, with any form of angular crank or wobble plate mechanism, each piston arrives at its dead center position when the plane of the angular crank is radial to the particular 15 cylinder, and that, (referred to crank angles) the "exhaust" piston in the sleeve 18a will lead the "inlet" piston in the sleeve 18b by the angle which these cylinders subtend from the center of the engine.
- 20 Connected to the collecting belt around the inlet ports 18b is an inlet pipe 38 and similarly connected to the belt around the exhaust ports 18a is the exhaust pipe 40. This disposition is 25 repeated at the other pairs of cylinders, the specific showing of the drawings illustrating three pairs of cylinders at either end of the engine.

The point of maximum effective displacement of the two out-of-phase pistons in any pair of cylinders is when the plane of the angular crank 30 is midway between those cylinders and this is the instant of ignition whereby the power impulses from one end of an engine with three pairs of cylinders will be spaced at 120° apart, the impulses at the other end occurring at the intermediate points 60° from those of the first end, due to the fact that opposed pistons reach the outer end of their strokes 180° apart, and herein 35 will be seen the reason for using an odd number of pairs of cylinders in the case where the common combustion chambers at the front and back 40 of the engine are disposed one opposite to the other. This disposition thus gives evenly spaced firing impulses although the individual cylinders are not evenly spaced and it will be seen that 45 this uneven spacing affords room for the exhaust pipes 40 and inlet pipes 38 within the general overall diameter of the engine which is thus unusually compact.

Referring now to Figure 3 which shows one 50 pair of cylinders in section, with the piston of the rear inlet cylinder at its outer dead center, the out-of-phase of the pistons is illustrated so that it may be seen that the exhaust ports will be opened and closed before the inlet ports. In 55 this figure it is also shown that each inlet pipe 38 comprises the elbow 38a communicating with the inlet belt of the front cylinder and a T 38b communicating with the inlet ports of the rear cylinder and connected to the elbow 44 of a 60 scavenging blower or supercharger 46 which is provided with an impeller 48 driven at high speed thru gearing (not shown) and having an air inlet duct 50, better seen in Figure 1. The exhaust pipes 40 similarly include elbows 40a communicating with exhaust ports of the front cylinders and T's 40b communicating with exhaust ports of the rear cylinders and provided with outlet pipes 40c. In Figure 3 a propeller 52 has been 65 shown as secured to the crankshaft 22.

70 Referring again to Figure 1, it will be seen that counterweights 54 and 58 disposed at 180° to each other are secured at opposite ends of the crankshaft by which means the rotating couple characteristics of angular crankpin or wobble 75 plate engines may be completely balanced.

It will also be seen that the cylinder disposition of this invention is applicable to two-cycle operation with any known means for preparing the fuel charge.

80 Regardless of the fuel system used, this invention provides an extremely compact engine having paired cylinders for two cycle operation, thus realizing the good scavenging characteristics of the widely separated inlet and exhaust ports, while it achieves at the same time good balance and even spacing of the firing impulses in combination with the out-of-phase piston motion desired for the proper timing of the inlet and exhaust ports.

85 While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

90 What is claimed is:

1. In an engine, in combination, a power shaft, a plurality of cylinders united in pairs by common combustion chambers at each end of the engine and arranged around and parallel to the power shaft, the circumferential spacing of adjacent cylinders between pairs being greater than the spacing of the cylinders of a pair, one cylinder of each pair having inlet ports and the other cylinder of each pair having exhaust ports, double-ended pistons working in said cylinders and adapted to overrun said ports in said cylinders, and pipes connected to said ports and disposed in the spaces 100 between adjacent pairs of cylinders substantially within the overall diameter of the engine.

105 2. In an engine, in combination, a power shaft, a plurality of cylinders united in pairs by common combustion chambers arranged around and parallel to the power shaft, the circumferential spacing of adjacent cylinders between pairs being greater than the spacing of the cylinders of a pair, one cylinder of each pair having inlet ports and the other cylinder of each pair having exhaust 115 ports, pistons working in said cylinders and adapted to overrun said ports, and intake and exhaust manifolds connected to the respective ports and disposed in the spaces between adjacent pairs of cylinders substantially within the overall 120 diameter of the engine.

125 3. The combination, in an internal combustion engine, of a power shaft, a casing within which said power shaft is enclosed and beyond one end of which said power shaft extends, a plurality of 130 cylinders within said casing, said cylinders being united in pairs by common combustion chambers and being arranged around and in parallelism with said power shaft, the circumferential spacing of adjacent cylinders between pairs being greater than the spacing of the cylinders of a pair, one cylinder of each pair having inlet ports and the other cylinder of each pair having exhaust 135 ports, pistons operating within said cylinders to overrun said ports, a supercharger fastened to said casing at that end thereof within which the common combustion chambers are formed, and intake and exhaust manifolds fitted in the spaces between adjacent pairs of cylinders substantially within the overall diameter of the engine, said manifolds being open respectively to said supercharger and to the intake ports on the one hand and to the exhaust ports on the other.

140 4. In an internal combustion engine, a power 150

shaft, cylinders arranged around and in parallelism with said power shaft, a casing within which said cylinders are enclosed and from one end of which said power shaft extends, said casing comprising a plurality of casing sections having bolts common to the total number thereof extending therethru to fasten said sections together, said bolts being disposed circumferentially about said power shaft, and one said casing section having formed therein a recess, and a counter weight fastened to said power shaft and rotatable within said recess. 80
